Primary Examiner — Janice Seeger(74) *Attorney, Agent, or Firm* — Christie, Parker & Hale,
LLP(57) **CLAIM**The ornamental design for a dual display, as shown and
described.**DESCRIPTION**

FIG. 1 is a front perspective view of a dual display;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is an exemplary diagram of a use of the dual display, in
which a musical score and a keyboard are displayed on a
display unit.
The broken lines in the drawings are for illustrative purpose
only and form no part of the claimed design.
